UNITED STATES PATENT OFFICE.

PASCAL J. SHAMPAY, OF CHICAGO, ILLINOIS.

CLEANING MACHINE.

Application filed March 18, 1920. Serial No. 366,927.

To all whom it may concern:

Be it known that I, PASCAL J. SHAMPAY, a citizen of the United States, and a resident of the city of Chicago, in the county of Cook and State of Illinois, have invented 5 certain new and useful Improvements in Cleaning Machines, of which the following is a specification.

My invention relates to cleaning machines, and has for its object the provision of a simple and efficient device of the character mentioned.

A further object is the provision of a simple and efficient cleaning device adapted 15 to hold the articles to be cleaned in tubular form while being cleaned.

A still further object of the invention is the provision of means for holding an article to be cleaned in tubular form, rotating said 20 article to be cleaned about a vertical axis and discharging a cleaning fluid by centrifugal force against said article to be cleaned.

A further object is the provision of a plurality of receptacles having cleaning elements therein mounted on an axis so that the receptacles can be rotated about said axis to bring each of the cleaning elements in position for being operated by driving mechanism.

30 A still further object is the provision of a simple and efficient driving connection for connecting a power means with a cleaning element, such as set forth hereinafter.

A still further object is the provision of 35 annular supporting means for supporting an article to be cleaned in tubular form.

Other objects will appear hereinafter.

An embodiment of my invention is indicated in the accompanying drawings forming 40 a part of this specification, and in which,

Fig. 1 is a side elevation of a device embodying my invention.

Fig. 2 is an enlarged fragmental view 45 taken as looking from line 2-2 in Fig. 1.

Fig. 3 is a vertical section taken through one of the cleaning elements of my device.

Fig. 4 is a section taken on lines 4-4 of Fig. 3.

50 Fig. 5 is a partial bottom view of the rotating washer element and section of a post upon which said element is mounted viewed as from line 5-5 in Fig. 3.

Fig. 6 is a plan view of the device shown 55 in Fig. 1.

Fig. 7 is a fragmental plan view of one of the articles to be cleaned holding elements.

Fig. 8 is a section taken through the lower ring member for holding the article to be cleaned, and

60

Fig. 9 is a view similar to Fig. 8 but showing the locking means in operative position.

Referring more particularly to the drawings, I have indicated a base 10 having an 65 upright post 11 thereon. Adjacent the upper end of the post 11 are arms 12 having bearings 13 at their outer ends. In the bearings 13 is journaled a driving shaft 14 having a pulley 15 at its upper end for engagement with a belt, not shown.

Adjacent the lower end of the post 11 are two frame members 16 with a friction-alleviating bearing 17 between the lowermost of the frame 16 and the base 10. The 75 bearing 17 may be of any desirable form. The frames 16 are provided with annular end portions 18 and in each of the end portions 18 of the members 16 is a tubular wall 19 adapted to hold a cleaning fluid. Each 80 of the lower members 18 has a valve 20 connected therein so as to drain the receptacle formed by the lower member 18 and tubular walls 19.

In each of the parts 18 of the lowermost 85 member 16 is a depression in which is secured a collar 21 and in said collar is an upright post 22 providing a vertical axis for a rotary cleaning device within a wall 19. It will be apparent that the member 21 90 may be dispensed with and the post 22 mounted directly in the bottom of the part 18 when so desired.

Disposed around the post 22 is a tubular member 23 having its top end 24 closed. 95 Between the top 24 and the top of post 22 is a ball-bearing 25 of any desired type. Also between the sides of the tube 23 and its post 22 are bearing members 26 which may be of any kind of bearing material for alleviating friction. At the lower end of each tube 23 is a disc-shaped bottom member 27. In the present instance, the outer edges of the disc 27 are shown extending upwardly slightly so as to form a somewhat dish-shaped disc. However, the shape of the disc may be changed to suit different requirements.

On the disc 27 are mounted two walls 28 and 29 having openings therein and sub- 110

stantially concentric with each other and the tube 23. I have shown the wall 28 as being of perforated material and the wall 29 as being of coarse woven fabric, but it 5 will be understood that these walls may be made up of any desirable material, the important thing being that they are of such material as will permit the easy passage of the cleaning fluid therethrough.

10 To the top of the outermost wall 28 I secure an upwardly extending brake member 30, and on an adjacent part of the upper member 18 I provide a pin 31 to which is pivoted two brake bands 32, semi-circular in form. At the opposite side from pin 31 on said member 18 is a clamping device 33 so that after a cleaning device has been in operation and it is desired to stop the rotary movement thereof, the operator moves the handle of locking device 33 to clamp the brake bands 32 on the brake member 30.

Between the circular wall 29 and the tube 23 are one or more spirals 34 which preferably have their edges secured in any desirable manner to the walls 29 and 23 although the spirals 34 may be secured to only one of the walls 29 or 23 when so desired. The spirals 34 extend down through 30 the disc 27 and terminate in a scoop 35 which has its lower edge adjacent the bottom of the receptacle and the top edge of lower member 18 so that as the cleaning element rotates the scoop 35 picks up the 35 cleaning fluid from the bottom of the receptacle and carries it up the spiral to the top of the latter. As the cleaning fluid passes up the spiral portions thereof pass out through the foraminous wall 29 toward 40 the wall 28.

At the top of the tube 23 is attached a conical clutch member 36. This clutch member 36 may be made of any desirable material such as pressed fibre or paper. 45 On the lower end of the shaft 14 is a clutch member 37 splined on said shaft to move vertically onto and off of the clutch member 36. I find it advantageous to provide a compression spring 38 around the shaft 50 14 to normally press the clutch member 37 down toward clutch member 36. When it is desired to disconnect the driving shaft from the cleaning device, a lever 39, which is pivoted at 40 on a bearing 13, can be 55 pressed downwardly to raise the clutch member 37 by means of links 41 and a band 42, see Fig. 1. When the clutch member 37 is drawn up on shaft 14 one receptacle may be passed from under shaft 14 60 and the other receptacle brought under shaft 14 for operating the cleaning device in the latter. Thus, while the cleaning device in one receptacle is in operation, articles to be cleaned may be taken from and 65 other articles put in the other cleaning de-

vice. It will also be understood that as many receptacles as may be desired may be mounted on the members 18 by properly forming said members.

At the top and bottom of wall 28 are 70 ledges or shoulders 44 and 43 upon which the article-to-be-cleaned holding devices are mounted. In the present instance, I have indicated this article-to-be-cleaned holding device as comprising two annular members 75 each made up of an angular or Z-bar construction 45 in cross section, as clearly illustrated in Figs. 8 and 9. In this form of holder I preferably provide a plurality of openings 46 in each member 45 so that the cleaning fluid thrown from the spiral 34 can pass through said openings to contact the edges of the article to be cleaned, as clearly indicated at 47 in Fig. 9. Also, when the cleaning fluid falls or runs down 80 onto the top of the horizontal portion of member 45, such cleaning fluid can drain 85 out through openings 46 during the drying operation. Each member 45 is provided with a plurality of points 48 which preferably extend radially out from the axis of the cleaning element. It is easier to place the article to be cleaned on the points when pointed in this direction although they may be pointed in other directions when so desired. As a means for keeping the article to be cleaned on the points 48, I provide 90 annular members 50. These members 50 may be attached to the members 45 in any desirable manner. I have indicated slots 95 51 in the members 50 with screws 52 threaded in the members 45 and disposed within the slots 51 so that by loosening the screws, the members 50 may be slipped 100 downwardly to the position indicated in Fig. 8 for placing on and taking off the article to be cleaned and in Fig. 9 I have shown a member 50 in position for holding the article to be cleaned on points 48. It will be apparent that the screws 52 can 105 be tightened to hold the members 50 in either of these positions. One of the article-holding members rests on each of the ledges 43 and 44, as clearly indicated in Fig. 3. On the upper member 50 I have indicated 110 a ledge 53 which rests on the shoulder 44 for supporting the upper annular-holding member.

On the clutch member 37 I provide a disc-shaped flange 54 which covers over the interior of the upper article-to-be-cleaned support so as to prevent the cleaning fluid from splashing or being thrown out of the receptacle. When so desired a flange 55 may be provided on the bottom of flange 54 for engaging the top of wall 29 for supporting the latter in upright position. Also, the upper member 18 may be provided with a downwardly extending flange 56 for helping divert the cleaning fluid downwardly so 115 120 125 130

as not to pass out of the opening between members 30 and 18.

In the base 10 I pivot a latch 57 as at 58. This latch has a lug 59 extending up through 5 the base 10 in the path of a projection 60 on the bottom of each of members 18. The lug 60 is indicated in Fig. 2 as having an inclined part 61 adapted to be engaged by the part 59 so that when the members 16 are 10 swung around on the post 11 member 59 will yield downwardly riding over the inclined part 61 and stopping against the square shoulder 62 so as to arrest the rotary movement of the member 16. This locking 15 device holds the receptacle in proper position for operation by shaft 14. When it is desired to change receptacles, lever 39 is pressed downwardly to disengage the shaft from the cleaning device and the members 20 16 rotated on shaft 11 to bring a new receptacle into operative position over the base 10. It will be apparent that the operator must press down on foot pedal 63 to free member 60 from member 59 to permit rotation of member 16. The operator then frees 25 foot pedal 63 so as to permit the part 60 to slide over the inclined surface 61 and against the square shoulder 62 to stop the next receptacle as it passes over the base 10 for 30 operation of the cleaning device by shaft 14.

This machine is particularly adaptable for washing bed blankets and the like. The blankets, or other articles to be washed, are wound around on and attached to the ring 35 holders and lowered into the washing receptacles. They may be wound in one or more turns and if the tubularly formed blankets and the like are longer than the length of the walls 19, these articles to be washed may 40 lie in folds between the upper and lower rings.

I claim:

1. Cleaning apparatus comprising a receptacle; a cylinder rotatably mounted on a 45 vertical axis in said receptacle and having openings in its walls; an article-to-be-cleaned holder adapted to hold an article in spread-out condition against the inner periphery of said cylinder; and means for raising a cleaning 50 fluid from the bottom of said receptacle and discharging such cleaning fluid centrifugally toward said cylinder.

2. Cleaning apparatus comprising a receptacle; a cylinder rotatably mounted on a 55 vertical axis in said receptacle and having openings in its walls; rings at the top and bottom of said cylinder adapted to hold an article to be cleaned in spread-out condition adjacent the inner wall of said cylinder; and means for discharging the cleaning 60 fluid radially from the axis of said cylinder toward an article to be cleaned and facilitate holding the latter tightly against the inner wall of said cylinder.

3. Cleaning apparatus comprising a re-

ceptacle; a cylinder rotatably mounted on a vertical axis in said receptacle and having openings in its walls; blanket holding rings held in position by gravity at the top and bottom of said cylinder at the inner side of the latter; and means for discharging a cleaning fluid radially toward said cylinder. 70

4. A cleaning machine comprising a receptacle; a vertical post in the receptacle; a rotary member journaled on the post; means 75 in the rotary member for suspending an article to be cleaned in spread out tubular form around the vertical post; and means at the central portion of the rotary member for picking up a cleaning fluid from the bottom of the receptacle and discharging said cleaning fluid against substantially all of the article to be cleaned at the same time. 80

5. A cleaning machine comprising a rotary member having two substantially concentric foraminous walls; an annular support concentric with the foraminous wall and adapted to hold an article to be cleaned in spread out tubular form between said walls; and a spiral having its periphery engaging the inner foraminous wall and having its lower end adapted to pick up a cleaning fluid below the bottom of said rotary member. 90

6. A cleaning machine comprising a receptacle; a vertical post in the receptacle; a tubular member rotatably mounted on the post; a substantially dish-shaped bottom attached to said member; two substantially concentric foraminous walls extending up 100 from said bottom; a scoop attached to said bottom and reaching down adjacent the bottom of said receptacle; a spiral extending upwardly from said scoop and attached to said tubular member and the innermost of 105 said walls; shoulders adjacent the top and bottom of one of said walls; a ring on each of said shoulders; and means on each ring for holding an article to be cleaned in tubular form between the foraminous walls. 110

7. A cleaning machine comprising a base; a post on the base; a plurality of receptacles pivotally mounted on said post and adapted to swing over said base; rotary cleaning mechanism in each receptacle; a power shaft 115 journaled on said post over said base; clutch mechanism for engaging said shaft with either of the cleaning mechanisms; means tending to hold the clutch mechanism in operative engagement with one of the cleaning mechanisms; and means for disengaging the clutch mechanism from said cleaning mechanism. 120

8. A cleaning machine comprising a rotary member; means in said rotary member 125 for discharging a fluid radially against the lateral walls thereof; and an article to be cleaned holding ring angular in cross-section disposed substantially concentrically with the axis of said rotary member and having 130

outwardly extending openings therein affording passages for conveying a liquid to the portions of the article to be cleaned engaging said ring.

- 5 9. Cleaning apparatus comprising a cylindrical washer housing; spaced-apart rings mounted in said housing; article to be washed helders on said rings; and means in the washer housing engaging said rings and co-operating with the latter and said holders for holding the article to be washed in stretched tubular form during the washing process.
- 10 10. The combination with washing apparatus, of two spaced-rings having points thereon adapted to engage and hold an article to be washed in tubular form and permit the placing into and removal from operative position in said washing apparatus of the article to be washed while thus attached to said points.
- 15 11. Cleaning apparatus comprising a cy-

lindrical container; a foraminated cylinder rotatably mounted about a vertical axis; rings mounted adjacent the top and bottom 25 of said foraminated cylinder; points on said rings, said rings and points being adapted to hold an article to be washed in tubular form and easily removable from adjacent the foraminated cylinder; and means for discharging a cleaning fluid radially between said rings toward said foraminated cylinder.

12. Cleaning apparatus comprising a washing mechanism container; two spaced rings; and points fixed on said rings, said rings and points being adapted to receive an article to be cleaned in tubular form before introducing the latter into said container and holding said article to be cleaned until removed from said container.

In testimony whereof I have signed my name to this specification on this 11th day of March, A. D. 1920.

PASCAL J. SHAMPAY.
